UNITED STATES PATENT OFFICE.

QUIRINO ANGELILLI, OF NEW YORK, N. Y.

BRICKLAYER'S GUIDE.

Application filed November 30, 1926. Serial No. 151,794.

The invention generally relates to guide devices adaptable for use by bricklayers for guiding the laying of brick in the construction of buildings and primarily has for its object to provide a bricklayer's guide of simple and compact construction, economical to manufacture and practical in its adaptation for use in guiding the laying of brick at the corners of a building and for carrying and moving the usual guide line.

As is well known, it is the present common practice to raise the corners of a building in successive steps in advance of raising the intervening walls in accordance with the raised corners. In an effort to assure evenness in the wall construction, only the most expert of the bricklayers are given the task of raising the corners. Even with this precaution it frequently happens that appreciable difference in mortar thicknesses occur and one corner may comprise more courses than its accompanying corner, rendering impossible the laying of registering courses between them and necessitating the tearing down and rebuilding of at least one such corner.

This practice of raising the corners first also causes the bricklayer to work without knowing definitely the exactness of his accomplishment. He must frequently test his work and finding inaccuracies he endeavors to put it in plumb by hammering. This loosens the mortar already set, and the bricks remain detached with their weight alone holding them in position.

Also, in the practice mentioned nails are driven into the wall to hold the guide line. This occasions detachment of the bricks and leaves holes in the walls.

It is to efficiently overcome the above faults and to provide additional advantages that I have devised my mechanical guide by the use of which a wall may be uniformly raised by workers of ordinary skill, with ease and the assurance of perfect accuracy in the work.

In its more detailed nature the invention seeks to provide a device of the character stated wherein is provided a corner guide upright, means to mount said upright in operative position upon the building, a guide scale having a plurality of selective faces carried by the upright in a manner permitting presentation of a selected face to view, and means on said upright for carrying a

guide line in a vertically adjustable manner, and means for rendering the line taut without vertically moving said carrying means.

With the above and other objects in view that will hereinafter appear the invention still further resides in the novel details of construction, combination and arrangement of parts, all of which will be first fully described, then be particularly pointed out in the appended claims, reference being had to the accompanying drawings, in which:

Figure 1 is a perspective view illustrating the invention in use upon an outside building corner.

Figure 2 is a view similar to Figure 1 and illustrates the invention in use upon an inside building corner.

Figure 3 is a plan view of the parts shown in Figure 1.

Figure 4 is a side elevation illustrating the lower portion of the corner attachment and the line carrier applied to an outside building corner.

Figure 5 is a detail plan view illustrating an outside corner upright and its line carrier.

Figure 6 is a detail plan view illustrating an inside corner upright and its line carrier.

Figure 7 is a side elevation illustrating an outside corner upright per se.

Figure 8 is a detail cross section taken across one side arm looking toward one side bracket.

Figure 9 is a detail side elevation of a portion of a line carrier.

Figure 10 is a somewhat diagrammatic plan view illustrating the manner of mounting the upright in making an addition to a corner of a building.

Figure 11 is a plan view of the invention in use in making an addition to a building in the nature of a projection from a wall thereof, a modified form of support bracket and line carrier being shown.

Figure 12 is a detail plan view illustrating the upright and bracket shown in Figure 11.

Figures 13 and 14 are diagrammatic edge views illustrating the modified form of line carrier shown in Figure 11 and the manner of mounting and removal of the same.

Figure 15 is a fragmentary elevation of an end portion of an upright mounting side arm.

Figures 16 and 17 are detail perspective views illustrating modified forms of the adjustable scale or course divider in each of

which means is shown for providing eight selective course dividing scales 3^x and 3^y respectively.

In the drawings, 1 represents the corner guide upright which may be constructed of any suitable material, wood for example, and which is substantially diamond shape in cross section and has that corner or edge thereof which is adapted to be presented toward the corner being built provided with a right angled notch 2 which, in the construction of the said corner, serves to guide and position the merging extremities of the bricks forming the center.

One face of the upright 1 may be provided with a suitable scale 3, preferably a repeated standard foot scale, as indicated in Figure 7 of the drawings. This scale serves to quickly indicate the height of the wall or story being built or portion thereof.

To further provide for effectively guiding the courses the upright is provided with a vertical bore 4 formed adjacent one face thereof, the interior of which may be viewed through the window 5 formed in the upright face mentioned and communicating into the said bore. In the bore 4 is mounted an adjustable scale 6 having a plurality (four being shown) of scale faces, the said scale 6 being rotatable in the bore so that any selected one of the plurality of scale faces may be presented to view through the window 5. It is to be understood, of course, that each of the scale faces bears a differently divided guiding scale adaptable for guiding the laying of different sized courses formed of varying thicknesses of bricks and varying thicknesses of mortar. To this end, the scale faces may be as many in number as may be desired and sub-divided in any suitable manner in accordance with the needs of the most common uses to which the device is put.

At its lower end the upright 1 is provided with a central depending mounting lug 7 threaded as at 8 and carrying an adjustable rest nut 9, the purpose of which will presently appear.

Another mounting lug 10 is projected outwardly from the outermost corner of the lower end of the upright and depends therefrom in the manner illustrated in Figures 4 and 7.

When the upright 1 is mounted for use the depending lugs 7 and 10 pass through apertures 11 formed in the rest and mounting bracket 12, the inner extension of which is embedded in the wall in the manner indicated in Figures 3 and 4. The provision of the lugs 7 and 10 and the manner of mounting them as just described assures against loss of position of the upright by any twist action.

The central lug 7 also passes through apertures 13 formed in the respective ends of

the angle iron side arms 14, the said ends being lapped and resting on the bracket 12 beneath the upright 1.

This manner of mounting serves to anchor the said side arm ends, and the said lapped ends form a rest for the adjustable nut 9. It will be understood that by reason of providing the adjustable nut rest for the upright, by turning the said nut the upright may be raised or lowered to provide a considerable vertical adjustment thereof as may be necessary or desirable in the use of the device in some instances.

One or both of the angle iron side arms may be braced to the bracket 12, if desired, as indicated at 15, and to further strengthen the bracket 12 the same may be provided with a vertical leg portion 16 adapted to lie flatly against the wall being constructed and which is suitably braced as at 17.

The side arms 14 lie flatly against the side of the wall being constructed and the extended end of each thereof is supported upon a bracket 18 which like the bracket 12 has a portion thereof embedded in the wall and a vertical portion 19 suitably braced as at 20. The said side arm ends are each provided with a suitable slotway 14* through which the embedded portion of the bracket 18 may pass, see Figure 15.

In practice the upright 1 is preferably constructed twelve feet in length. About three feet from the uppermost end of the upright a brace connector 21 is secured and to each end of the said connector a brace rod 22 having turn-buckle equipment 23 is secured and connects with the outwardly projected end of the bracket 18 at that side of the corner, thus serving to rigidly brace and position the upright and to hold the device in rigid relation.

To provide for adjusting the scale 6 to present a selected face thereof to view through the window 5 the same may be provided at its lower end with a depending stem 24 which may be projected through the lower end of the upright 1 and provided with a turning wheel 25 that may be readily rotated to change the position of the said scale for the purpose described, see Figure 4.

In practice when the device is being used as an outside corner guide the same is mounted in the manner illustrated in Figure 1 of the drawing in which case the selected scale of the member 6 serves in the manner illustrated to guide the courses of the wall and the thickness of the mortar joints.

To provide for suitably carrying the usual guide line for guiding the laying of the courses between the mechanically guided corner 1 I provide a line carrier block 26 vertically slidable upon the upright 1 and which may be secured to any selected position along the upright by the clamp screw 27. The carrier is provided with a suitable

window 28 through which the selected scale of the member 6 may be viewed and for suitably carrying the line the said carrier is equipped with a line winding drum 29 rotatably mounted upon the said carrier as at 30 and including the turning handle 31 by which rotation may be imparted to the said drum.

The carrier and drum are provided with 10 releasable back check pawl devices 32 which permit rotation of the drum in a direction effecting winding in or tightening of the line but serving to check any tendency of the drum to rotate in the opposite direction. 15 Suitable guide rollers 33 are mounted on the carrier which serves not only as anti-friction means but also to position the line close to the wall in the manner illustrated in Figures 3, 4, and 5. The line is indicated at 34.

In using the line carrying feature of the invention the carrier blocks of the uprights at two corners of the building are vertically adjusted to a like suitable position upon the 25 uprights when the said blocks are secured to the adjusted position and the winding drums thereof rotated to draw the line taut. The back check pawl device serves to hold the drums against back rotation, thus keeping 30 the line in its taut condition. By using my improved guide in this manner it is unnecessary to build up the corner in advance of the remainder of the wall as the whole wall may go up course by course guided not 35 only at the corners but also along the whole wall, thus ensuring perfectly even and uniform construction.

In Figures 2 and 6 I have illustrated a 40 modified form in which the principles of the invention are adapted for use in guiding the construction of an inside corner. In this adaptation of the invention the upright is formed substantially spear-head in cross section to more readily fit into the corner 45 being constructed. Otherwise the construction of the parts forming the device are substantially the same as those hereinbefore described and the said parts are indicated by the same numerals as those used to describe the parts of the first mentioned form and with the index letter "x" added thereto. With this explanation further detailed description of the parts of this modification is deemed unnecessary. In this form of the 50 invention the brace connector 21^x is projected straight inwardly from the inside corner of the upright 1 and the brace rods 22^x are connected directly to the end thereof. To prevent any tendency of the brace rod bending 55 the upper end of the upright inwardly, supplemental braces 35 may be connected between the said rods and the inner end of the said connector in the manner indicated in Figure 6.

60 In Figures 11 and 12 of the drawings I

have illustrated the invention in use for guiding the construction of an addition projecting at right angles to and intermediately of the ends of a wall or building and in these figures I have illustrated a modified form 70 of mounting bracket. In Figure 11 referred to, and also in Figures 13 and 14, I have disclosed a modified form of line carrier member which may be employed if desired. 75

In the figures referred to, 36 represents the modified form of line carrier which includes the usual anti-friction and guide rollers 37, and tightener pulley 38 for carrying and positioning the line 39. It will be observed that as in other forms the line carrier is in the nature of an open frame for partially encircling the upright, the opposed sides of the frame, however, engaging the opposite sides of the upright on different planes, as shown in Figure 13 of the drawings and the said sides being connected by a connecting piece which when mounted normally, as indicated in the figure referred to, bears an angular relation to the upright. Thus, when the carrier is normally mounted, as indicated in Figure 13, it snugly fits the upright as may be seen by reference to Figure 11 but when the carrier is turned to the position illustrated in Figure 14 to bring the connecting piece to a substantially horizontal position the sides of the carrier move away from the sides of the upright and the carrier may be readily withdrawn from the upright. 90 95

To provide for securing the carrier at adjusted positions along the upright one side thereof is provided with a key receiving socket 40 inclined downwardly toward the upright and which is adapted to receive the securing key 41 which, when the parts are mounted as illustrated in Figure 13, extends downwardly through its socket into frictional engagement with the upright for securing the carrier at a desired position. By withdrawing the key as illustrated in Figure 14 100 the carrier may be removed in the manner hereinbefore described. 105

In this use of the invention the upright may be mounted upon a mounting bracket 42 which, like the mounting brackets hereinbefore described, has a portion adapted to be embedded in the wall being constructed, but in this case, in order not to interfere with the wall to which an addition is being made, the portion 43 to be embedded is offset in the manner clearly illustrated in Figures 11 and 12 so as to be embedded only in the wall being constructed. 110 115

When it is desired to extend one wall forming a corner of a building, the invention is applied for use in the manner illustrated in Figure 10. In the common use of the invention in constructing a corner as illustrated in Figure 1 of the drawings, the notch 2 formed in the upright 1 serves to 120 125 130

receive the corner of the bricks. Obviously the vertical groove 2 cannot so function in the use of the invention now being described as it would bring a portion of the upright 5 into interference with the bricks being laid. To obviate this, I provide a corner extension strip 44 which is fitted into and secured in the vertical groove or notch 2 in the corner as illustrated in Figure 10, which said strip 10 is provided with a notched portion 45 which serves as an extended substitute for the notch 2 and which effectively serves to position the upright beyond the wall in the manner illustrated. In this use of the upright 15 the same may be mounted upon a mounting bracket 46, the extended portion of which may be embedded in the wall, as indicated and which may have a notched or cut out portion 47 to prevent interference 20 with the bricks forming the corner of the old building.

As illustrated in Figure 8 of the drawings each rest bracket hereinbefore described may be provided with a notched portion 48 25 around which an anchoring wire 49 may be looped, the free ends of the said wire being embedded in the wall to assure firm anchoring of the brackets to their desired positions. When such anchoring wires are utilized they 30 may be cut off upon completion of the wall and the small holes formed in the wall by reason of their position suitably filled.

From the foregoing description, taken in connection with the accompanying drawings, 35 it is thought that the novel details of construction, the manner of use and the advantages of my invention will be readily apparent to those skilled in the art to which it relates.

40. What I claim is:

1. In a device of the class described, a corner guide upright, means for mounting said upright in operative position upon the building, and a guide scale carried by said 45 upright and having a plurality of differently graduated faces, said upright and said scale having associated means for exhibiting one face of the scale at a time, for the purposes described.

50. 2. In a device of the class described, a corner guide upright, means for mounting said upright in operative position upon the building, said upright having a longitudinal bore therein and a window through which 55 the interior of said bore may be viewed, and a multi-faced scale member movably mounted in the bore in a manner permitting presentation of any selected face of said scale member to view through said window.

60. 3. In a device of the class described, a corner guide upright, means for mounting said upright in position upon the building, a guide scale on said upright, a vertically adjustable line carrier on said upright, a 65 line winding drum carried by the line car-

rier, and means for securing the drum at line wound positions against unwinding rotation.

4. In a device of the class described, a corner guide upright, means for mounting 70 said upright upon the building, a guide scale on said upright, a line carrier vertically slidable on said upright, a set screw to secure said carrier at adjusted positions, a line winding drum carried by the said carrier, back check ratchet and pawl devices for preventing unwinding rotation of the drum, and line guide anti-friction rollers carried by the carrier for positioning the line closely 75 adjacent and parallel the wall being laid.

5. In a device of the class described, a corner guide upright, means for mounting 80 said upright upon the building, a guide scale carried by said upright and having a plurality of differently graduated faces, said upright and said scale having associated means for exhibiting one face of the scale at a time, a line carrier vertically adjustable on said upright in association with the scale, 85 a line winding drum carried by the line carrier, and means for securing the drum at line wound positions against unwinding rotation.

6. In a device of the class described, a corner guide upright, means for mounting 90 said upright in operative position upon the building, a guide scale having a plurality of differently graduated faces, said upright having a recess, means for mounting said 95 guide scale in the recess to expose one face of the guide scale at a time, the remaining faces being hidden by the walls of the recess, said upright having a vertical guide notch in the edge presented toward the building 100 corner for the purposes specified.

7. In a device of the class described, a corner guide upright, a rest bracket beneath said upright to support the same and having a portion adapted to be embedded in the wall corner, angled rest brackets positioned in spaced relation to the upright supporting rest bracket and having a portion thereof adapted to be embedded in the walls at each side of the corner formed thereby, a brace 105 connector secured to the upright adjacent its upper end, adjustable brace rods connected between the angled rest brackets and the ends of the cross piece for positioning and bracing the upright, and side arms secured upon the rest brackets and adapted to lie against the walls forming the corner.

8. In a device of the class described, a corner guide upright, a rest bracket beneath said upright to support the same and having a portion adapted to be embedded in the wall corner, angled rest brackets positioned in spaced relation to the upright supporting rest bracket and having a portion thereof adapted to be embedded in the walls at each 115 side of corner formed thereby, a brace 120 connector secured to the upright adjacent its upper end, adjustable brace rods connected between the angled rest brackets and the ends of the cross piece for positioning and bracing the upright, and side arms secured upon the rest brackets and adapted to lie against the walls forming the corner.

5 nector secured to the upright adjacent its upper ends, adjustable brace rods connected between the angled rest brackets and the ends of the cross piece for positioning and 5 bracing the upright, and side arms secured upon the rest brackets and adapted to lie against the walls forming the corner, said side arms having their adjacent ends overlapped beneath the upright and upon its 10 supporting bracket, said upright having a central depending lug, and its supporting bracket and the lapped arm ends having registering lug receiving apertures to receive the depending lug, and an adjustable nut on said 15 lug for the purposes specified.

9. In a device of the class described, a corner guide upright, a rest bracket beneath said upright to support the same and having a portion adapted to be embedded in the wall 20 corner, angled rest brackets positioned in spaced relation to the upright supporting rest bracket and having a portion thereof adapted to be embedded in the walls at each side of the corner formed thereby, a brace 25 connector secured to the upright adjacent its upper ends, adjustable brace rods connected between the angled rest brackets and the ends of the cross piece for positioning and bracing the upright, side arms secured upon the rest brackets and adapted to lie 30 against the walls forming the corner, said side arms having their adjacent ends overlapped beneath the upright and upon its supporting bracket, said upright having a central depending lug and an outer depending lug, and its supporting bracket having a pair of apertures to receive both lugs, and 35 said lapped arm ends having apertures registering with one bracket aperture to receive 40 the central depending lug, and an adjustable nut on said lug for the purposes specified.

10. In a device of the class described, a corner guide upright, a rest bracket beneath said upright to support the same and having a portion adapted to be embedded in the wall corner, angled rest brackets positioned in spaced relation to the upright supporting rest bracket and having a portion thereof adapted to be embedded in the walls at each 50 side of the corner formed thereby, a brace connector secured to the upright adjacent its upper ends, adjustable brace rods connected between the angled rest brackets and the ends of the cross piece for positioning and bracing the upright, side arms secured upon the rest brackets and adapted to lie 55 against the walls forming the corner, said side arms having their adjacent ends overlapped beneath the upright and upon its supporting bracket, said upright having a central depending lug and an outer depending lug, and its supporting bracket having a pair of apertures to receive both lugs, said 60 lapped arm ends having apertures registering with one bracket aperture to receive the 65

central depending lugs, an adjustable nut on said lug, and a guide scale having a plurality of selective faces carried by said upright in a manner permitting presentation of a selected scale face to view. 70

11. In a device of the class described, a corner guide upright, means for mounting said upright upon the building, a line carrier mounted on said upright and comprising an open frame for partially encircling said upright, said carrier having sides which oppose the upright at different elevations and which are joined by a portion positioned in angular relation to the upright when in normal mounted position, whereby when in normal mounted position said sides will closely fit the upright but when moved to bring the connecting piece substantially horizontal said sides will move away from the upright and permit ready removal of the line carrier, means on said carrier for holding a line taut, and means for securing the carrier at adjusted positions on the upright. 80

12. In a device of the class described, a corner guide upright, means for mounting said upright upon the building, a line carrier mounted on said upright and comprising an open frame for partially encircling said upright, said carrier having sides which oppose the upright at different elevations and which are joined by a portion positioned in angular relation to the upright when in normal mounted position, whereby when in normal mounted position said sides will closely fit the upright but when moved to bring the connecting piece substantially horizontal said sides will move away from the upright and permit ready removal of the line carrier, means on said carrier for holding a line taut, one said carrier side having a key receiving socket, and a key insertable through the socket into engagement with the upright for securing the carrier to adjusted positions on the upright. 95

13. In a device of the class described, a corner guide upright means for mounting said upright in operative position upon the building, a guide scale on said upright, said upright having a vertical notch in the edge thereof adapted to be presented toward the building corner, and an angle-notched corner guide strip secured in said corner notch and adapted to receive the brick corners at the corner of the walls being constructed to guide said construction. 110

14. In a device of the class described, a corner guide upright, a rest bracket beneath said upright to support the same and having a portion adapted to be embedded in the wall corner, angled rest brackets positioned in spaced relation to the upright supporting rest bracket and having a portion thereof adapted to be embedded in the walls at each side of the corner formed thereby, a brace connector secured to the upright adjacent 125

its upper end, adjustable brace rods connected between the angled rest brackets and the end of the cross piece for positioning and bracing the upright, side arms secured upon the rest brackets and adapted to lie against the walls forming the corner, said rest brackets each having a wire mounting notch, and a wire adapted to be hooked into each bracket notch and anchored into the wall being built.

15. In a device of the class described, a

corner guide upright, means for mounting said upright in operative position upon the building, a guide scale having a plurality of differently graduated faces, said upright having a recess, and means for mounting said guide scale in the recess to expose one face of the guide scale at a time, the remaining faces being hidden by the walls of the recess.

QUIRINO ANGELILLI.
